GUIDE FOR CAN OPENING KEY AND TEAR STRIP

Joseph H. Bulger, Los Angeles, Calif.

Application July 26, 1949, Serial No. 106,801

2 Claims. (Cl. 220—52)

1

This invention relates to an improved clip to guide the winding onto can opening keys of strips which they sever from cans in opening the latter.

While it is not broadly new to provide guide means of the above stated kind, yet there remains room for improvement of such devices in respect to lessening manufacturing cost and reducing cost of assembly, and the waste of material caused by throwing the guide clip away each time a new can is opened. Also heretofore a disadvantage as resulted from attaching to a can-opening key, soldered to the end of a can, a strip guide which tends to interfere with stacking the cans snugly in an end to end fashion.

An object of the invention is to provide a wire clip which can be readily applied to and removed from a manually turnable key used to open sheet metal cans such as the type of can in which coffee is supplied to the consumer; the applied clip causing the strip to wind symmetrically onto the key and causing the strip to form a straight ended coil when wound onto the key.

Another object is to provide a guide clip of the above stated kind that can be detachably mounted upon the key so that, after it has been used in the operation of opening the first can it can be repeatedly reused by applying it to other can opening keys.

Still another object is to provide a clip of the above stated kind which adapts itself for use in winding onto can opening keys long as well as short strips, so that the clip can be used to advantage in opening cans differing greatly in diameter.

A more specific object is to provide a key guide clip which can be manufactured at a reduced cost owing to being so shaped as to render it unnecessary to provide a curl to secure the can opening key.

The invention pertains to a new article of manufacture usable in opening a considerable variety of different canned goods wherein the cans differ in size and shape.

Other objects, advantages and features of invention will hereinafter appear.

Referring to the accompanying drawing, which illustrates a preferred embodiment of the invention,

Fig. 1 is a perspective view of the device, per se.

Fig. 2 is an enlarged side elevation of the device operatively shown applied to a fragment of a vacuum type coffee containing can.

Fig. 3 is an underside plan viewed from line 3—3 of Fig. 2.

Referring in detail to the drawing, the device

consists of a single piece of stiff wire 5 the midlength portion of which is bent into a U shape which consists of a pair of arms 6 parallel to each other throughout their lengths joined at 5 the midlength of the wire by an arcuate run 7. This wire clip is symmetrically shaped, the arms of said U being continued as parallel runs 8 which extend at substantially a right angle in relation to the plane through which the U part is bent, and said arms 8 each having a terminal portion 9 which extends at considerably less than a right angle to the arm 8 at its side of the device. The arms 8 and 9 at each side of the clip are shown as substantially equal in length, each being slightly longer than the U arm 6 at the same side of the clip. Only a slight rounding 10 is presented at each side of the clip at the juncture of the runs 6 and 8 to form a seat at that point, but a more extended arcuate part 11 15 unites the runs 8 and 9, and said arcuate part 11 forms the bottom portion of a cradle wherein rests the key 14 when the clip is in its applied position, at which time the side portions of said cradle, formed by the arms 8 and 9, are positioned 20 25 astride the coil 15 so that they guide the winding of the severed strip onto the key.

As viewed in side elevation (see Fig. 3), each side portion of the clip is of a double V shape the bend 10 forming the apex of one V and the bend 11 forming the apex of the other V, the apices of the V's being oppositely directed and the wire run 8 being shared in common by the two V's. Or the clip may be described as comprising a single piece of rigid wire consisting of 30 parallel twin portions which are united at the midlength of the wire by a U bend, each of said twin portions consisting of an inner, a middle and a terminal run, the wire being bent in one direction at the junction of said inner and middle runs, and being bent in the opposite direction at the juncture of said middle and terminal runs, the wire being substantially straight between said bends.

Preparatory to operating the device the parallel bends 11 are abutted against the curved wall portion of the can 25 adjacent to its rim 26 with the free upturned end of the strip 15 between said bends 11. Then the slotted part of the key is fed onto the short, projecting strip end. 45 Fig. 3 shows how the key and partly coiled up strip 15 appear after winding-up operation has begun. As the severance operation continues around the can, the U bend 7 slides along the periphery of the can, and as the ruptured strip 50 winds on the key the tautness of the coil is in-

creased to the point of the force required to tear off the strip. Therefore, as the turning of the key continues the compactness of the turns of the coil is maintained and at the same time, as the coil builds up on the key, the ends of the coil are caused to lie in flat parallel planes.

I claim:

1. A strip guide clip applicable to can opening keys, said clip comprising a single piece of rigid wire consisting of parallel, twin, spaced apart portions which are united at the midlength of the wire by a U bend, each of said twin portions consisting of an inner, a middle and a terminal run, the wire at each side of said U bend being bent in one direction at the juncture of said inner and middle runs, and being bent in the opposite direction at the juncture of said middle and terminal runs, the wire being substantially straight between said bends.

2. The subject matter of claim 1 and, in each of said twin portions the bend at the juncture of the middle and terminal run being dimensioned and shaped to form a cradle to seat the can opening key.
